UNITED STATES PATENT OFFICE.

FOSTER MILLIKEN, OF LAWRENCE, NEW YORK.

DESIGN FOR A STREET SIGNAL LAMP.

Application filed February 21, 1922. Serial No. 813. Term of patent 14 years.

To all whom it may concern:

Be it known that I, FOSTER MILLIKEN, a citizen of the United States, and a resident of Lawrence, in the county of Nassau and State of New York, have invented a new, original, and ornamental Design for Street Signal Lamp, of which the following is a specification, reference being had to the accompanying drawing, forming part thereof.

Figure 1 is a perspective view of a street signal lamp showing my new design. Figure 2 is a sectional view through Figure 1 approximately on line 2—2.

I claim:—

The ornamental design for a street signal lamp, as shown.

FOSTER MILLIKEN.
